(57) **CLAIM**

We claim the ornamental design for a pet water fountain, as shown and described.

DESCRIPTION

FIG. 1 is an exploded perspective view showing our new design for a pet water fountain;

FIG. 2 is a perspective view showing just the bowl for the pet water fountain of FIG. 1. The view is seen from a first direction.

FIG. 3 is a second perspective view of the bowl for the pet water fountain of FIGS. 1 and 2. The view is seen from a second opposite direction wherein a bottom of the bowl is visible.

FIG. 4 is a front view of the bowl of FIGS. 2 and 3. The back view is identical to the front view.

FIG. 5 is a right side view of the bowl of FIGS. 2 and 3. The left side elevation view is a mirror image of the right side.

FIG. 6 is a top or plan view of the bowl of FIGS. 2 and 3.

FIG. 7 is a cross-sectional view of the bowl of FIG. 6, taken across line A-A.

FIG. 8 is a bottom view of the bowl of FIGS. 2 and 3.

FIG. 9 is a perspective view of just the tower for the pet water fountain of FIG. 1.

FIG. 10 is a front view of the tower for the pet water fountain of FIG. 9. The back view is identical to the front view.

FIG. 11 is a right side view of the tower of FIG. 9. The left side elevation view is identical to the right side.

FIG. 12 is a top or plan view of the tower of FIG. 9.

FIG. 13 is a cross-sectional view of the tower of FIG. 12, taken across line A-A; and,

FIG. 14 is a bottom view of the tower of FIG. 9.

Broken lines and portions contained within broken lines are not claimed.
